UNITED STATES PATENT OFFICE

116,815

DESIGN FOR A COMBINED SACHET AND SUPPORT OR SIMILAR ARTICLE

Raymond B. Darcey, Woonsocket, R. I.

Application January 20, 1939, Serial No. 82,475

Term of patent 3½ years

To all whom it may concern:

Be it known that I, Raymond B. Darcey, a citizen of the United States, residing in Woonsocket, Providence County, and State of Rhode Island, have invented a new, original, and ornamental Design for a Combined Sachet and Support or Similar Article, of which the following is a specification, reference being had to the accompanying drawing forming a part thereof.

Fig. 1 is a front elevational view of a combined sachet and support showing my new design; and Fig. 2 is an edge view of the same.

The dominant features of my design reside in the portions shown in full lines.

I claim:

The ornamental design for a combined sachet and support or similar article, substantially as shown and described.

RAYMOND B. DARCEY.
